22 Claims. (Cl. 61—46)

1

The present invention relates to improvements in marine towers and a method of transporting and positioning them, said towers being adapted for positioning on a water-bed and for supporting superimposed loads and working platforms therefor, such as beacons, offshore gun emplacements, observation posts, well drilling rigs and equipment, mining equipment for operations in water and in marshy locations, and for any other purposes which require a support that is positioned in and above water.

Heretofore, marine towers (whether assembled to their full length on shore or on a barge) and the methods of placing them, of which I have knowledge, have been such as required flotation or transportation of the towers in a vertical position to the desired location. This is a hazardous operation, particularly if storms or rough water are encountered. Furthermore, with this type of handling, a tower is liable to be distorted or damaged to a material extent, even to its total loss. In addition, such an operation requires the use of expensive and elaborate equipment, such as barge derricks, etc. In other types of towers, the methods of placing them in position on the water-bed include the flotation of a tower base to a location, sinking it to the water-bed and then erecting the tower vertically from the base. These towers also require the use of complicated devices and mechanisms, including divers, and, in some instances, caissons.

The important and principal object of the present invention is the provision of a tower of such design that it may be readily assembled, in a horizontal position, on shore and, which, when assembled, is capable of being floated, in a horizontal position, to the location where it is to be erected and placed on the water-bed. Consequently, the necessity of costly erection equipment is eliminated and a minimum of offshore operation is required, thereby eliminating, or greatly minimizing, the hazards of distortion of, or of severe damage to, the tower during transportation to the point of location. It is desirable that the tower be provided with floodable, buoyant devices, by means of which it may be erected to a vertical position whereupon it can be so manipulated as to settle upon the desired spot on the water-bed where it is to be anchored. By means of these same floodable, buoyant devices, the tower may subsequently be raised and moved to a new location, or it may be completely salvaged.

It is also an important object of the invention to provide a marine tower construction that comprises a plurality of spaced columns which are

2

disposed concentrically about a center opening so that the tower will be substantially circular in cross section with a central, unobstructed shaft extending from the top to the bottom thereof.

5 Furthermore, the tower is preferably composed of a multiplicity of interchangeable sections, each comprising sections of the spaced columns, the end of the columns of adjacent sections being removably secured together and the column sections of each tower section being held in position by vertical and horizontal bracing so as to make each tower section a unitary structure, but, nevertheless, without obstructing the hollow shaft in the center of the tower.

10 Another object of the invention resides in the provision of a tower base which is annular in form, and upon which the columns rest, the base being so designed and proportioned that loads are distributed concentrically and equally on the bed-bottom, the base being a hollow, watertight, buoyant member that is connected with standard equipment for flooding or blowing out the same as desired.

15 A further object of the invention is to provide a tower having reduced resistance to external forces, such as to water current and wind pressure, by forming the columns and bracing thereof with exterior surfaces which are rounded or circular in cross section.

20 Another feature of the invention is the provision of hollow, buoyant members, other than the base members, disposed along the length of the tower, at least one being positioned so as to be at or about, but preferably a slight distance below, the normal low water line of the tower, when the latter is resting on the water-bed. Another hollow, buoyant member may be disposed adjacent the base of the tower when it is desired to supplement the function of the base, either for providing added buoyancy or added weight, when the base is or is not to be flooded, for settling or fixing the tower in position or removing it therefrom. There may be other and intermediate hollow, buoyant members employed if desired or required. All of these buoyant members are circular or polygonal in shape and have a center opening so as to cooperate in forming the passage or shaft which extends vertically through the tower.

25 30 35 40 45 50 A still further object of the invention is to provide a sectional tower of the above described character that permits the ready removal or addition of sections as may be required according to the depth of the water in which the tower is to be placed, or according to the work to be performed.

Furthermore, by the use of fixedly positioned buoyant members (connected with conventional flooding and blowing out equipment) and anchors, and cables therefor, the entire structure may be lowered, or raised and moved to a new location, with a minimum of effort and equipment.

Other and further objects of the invention will be readily apparent when the following description is considered in connection with the accompanying drawings, wherein:

Figure 1 is a side view in elevation of the tower as it appears when in position in the water;

Figure 2 is a cross sectional view taken substantially on line 2—2 of Figure 1;

Figure 3 is a cross sectional view taken substantially on line 3—3 of Figure 1;

Figure 4 is a cross sectional view taken substantially on line 4—4 of Figure 1;

Figure 5 is an enlarged fragmentary side view in elevation of one of the vertical columns and the bracing rods associated therewith for rigidly uniting the several sections of the tower;

Figure 6 is a cross sectional view taken substantially on line 6—6 of Figure 5;

Figure 7 is a cross sectional view, similar to Figure 6, illustrating a channel pipe chase on one of the bracing rods;

Figure 8 is an enlarged cross sectional view, similar to Figure 2, with parts broken away to illustrate the construction of the supporting base for the tower;

Figure 9 is a cross sectional view through the base and is taken substantially on line 9—9 of Figure 8;

Figure 10 is a cross sectional view taken substantially on line 10—10 of Figure 9;

Figure 11 is a side view in elevation of the tower in position on a floating scow from which it is launched;

Figure 12 is an end view in elevation of the tower and scow illustrating the manner of releasably retaining the tower in position thereon;

Figure 13 is an end view in elevation illustrating the position of the tower and scow after one side of the scow has been flooded prior to launching the tower;

Figure 14 is a side view in elevation of the tower when it has assumed an upright position after being launched from the scow and after the base and/or adjacent buoyant member have been flooded, but prior to its settling on the bed of the body of water; and,

Figure 15 is a cross sectional view through the scow and illustrating the compartments therein, one of which is adapted to be flooded for launching the tower and thereafter blown out.

As shown in Figure 1 of the drawings, the present invention comprises a marine tower 16 which is made up of a series of sections 17. The sections are supported one above the other and the entire framework formed by these sections is carried on a base 18. Merely for the purpose of giving an indication of the proportions of the tower herein illustrated in Figure 1, the base is about 66 feet in diameter and five feet high with a central opening of about 46 feet in diameter; and the sections 17 are each approximately 25 feet in length or height and about 60 feet in diameter. Of course, it will be understood that these dimensions are given only by way of example and that they will be changed or varied according to changes in design or construction that may be desirable or required under varying circumstances and conditions.

The base 18, as more clearly illustrated in Figures 2, 8, 9 and 10, is ringlike and it may have polygonal sides or it may be a true annulus. As shown, said base comprises top and bottom plates 19 and 20 and side plates 21 and 22 which may be welded at their meeting edges. The base has a hollow, watertight interior to provide a floodable, buoyant member or chamber 18' and may accommodate any suitable type of reinforcing structure that will distribute the imposed vertical load thereon concentrically of the base. It is reinforced by a multiplicity of spaced cross beams 23 which form supports for the girders or eye beams 24 which are arranged in parallel relation and coextensive longitudinally with the walls of the base. Cross channel members 25 rest on the beams 24 at intervals, preferably, adjacent the ends of the beams 24. These members 23, 24 and 25 are secured together by suitable means, such as welding as one example.

Stub columns 26 are arranged in spaced relation on the top plate 19—preferably over these cross members 25—and the upper end of each is sealed by a circular plate 19a welded thereto and extending beyond the perimeter thereof to form a flange for receiving the pipe column of the lowermost section of the tower framework. A plurality of spaced cutting bars 28, attached to the bottom plate 20, are adapted for scouring a seat or bearing for the base structure on the bed of the water as the tower is brought into position.

From the above description of the base, it will be seen that the base is so designed that the imposed loads are directly over the bearing and that there has been provided a stiffened and reinforced watertight casing to form the base. These reinforcing elements are so designed and proportioned that loads are distributed concentric with the columns of the tower, and the center portion of the base is open to permit multiple drilling or other operations, or the erection of various structures. In order to provide access to the interior of the base, one or more manholes 28 have been provided in the top plate 19, and they may be closed by suitable watertight covers, not shown.

The base 18 may be used for adding buoyancy to the tower structure, or for adding weight thereto when positioning said structure on the bed of the body of water. Consequently, a pipe 29 extends from the base to a control point in the upper end of the tower, and is employed for flooding or venting the base when occasion demands or, in some instances, for supplying concrete to the interior of the base for increasing the weight and stability of the base when it has settled in position. In order to provide buoyancy, water is pumped from the base to the control point in the tower.

As previously indicated, the shaft of the tower comprises multiple superimposed sections 17, each section being identical in construction. Therefore, only one of the sections will be specifically described in detail, together with the manner in which it is united with an adjacent section. Each section 17 comprises a multiplicity of pipe columns 32 arranged in spaced relation and circularly about the axis of the section. The upper and lower ends of each pipe column carry a connecting member to which is attached vertical and horizontal struts. These members also provide means for uniting the sections by the use of bolts or the like.

Referring particularly to Figure 5 of the drawings which shows the connected adjacent ends

of two aligned columns 32 of two tower sections 17, it will be noted that the lower end 33 of each column 32 is sealed by a circular plate or disc 34 while the other end 35 of each column is sealed by a plate 36, the plates 34 and 36 being welded or otherwise attached in place so as to seal captive air within the hollow pipe column sections 32. The plate member 36 is generally triangular in shape and is truncated at its corners, and the upper end of the column is secured to the area of the apex portion of said triangular plate 36. The extending ends of the triangle 36 form lugs which have openings therein through which horizontal brace members may be secured.

The flange-forming portions of the plates 19a and 34 and the corresponding area of the plate 36 are designed to engage in abutting relation and each is provided with a circular series of matched openings to receive bolts 45 which secure the adjacent ends of aligned column sections together as well as the stub columns 26. Triangular vanes 37 and 39 extend upwardly from the plate 34 and downwardly from the plate member 36 as well as radially relative to their respective column sections 32, and each has one edge thereof welded or otherwise secured to its pipe section 32, as indicated at 38 and 40, respectively, and each may also be welded or otherwise fixed to the plates 34 and 36, respectively.

Bracing rods 41 are attached to the vanes 37 and 39 and are preferably diagonally disposed so as to cross one another, as shown in Figure 1 of the drawings, for vertically bracing adjacent column sections of each tower section. These bracing rods are shown as being provided with adjusting turn-buckles 42. Horizontal bracing rods 43 extend from the lug 36a on one column 32 to a similar lug in an alternate column and are secured thereto by bolts 43a. This arrangement of the horizontal bracing rods is more particularly shown in Figure 3 of the drawings; and said rods are also provided with adjustable turn-buckles 44. Additional horizontal struts 45 extend between and connect with adjacent lugs 36a by means of bolts 46.

Thus, the vertical bracing rods 41, horizontal bracing rods 43, and pipe struts 45, together with the vertical pipe columns 32, make up each section 17 of the shaft of the tower and the sections are joined together by bolts 47, as indicated in Figure 5 of the drawings, which pass through the plates 34 and 36. While the rods 41 and 43 are shown as being adjustable, they may be fixed, non-adjustable rods and they may be welded in place. It is to be noted that the column section 32, and the bracing rods 41, 43 and 45 are each circular in cross section so as to reduce their resistance to external forces, such as water currents and wind pressures.

Another feature of the invention resides in the use of chambered or hollow buoyant members fixedly positioned within the tower structure, and preferably on opposite sides of its center of gravity, whereby said structure may be floated horizontally, manipulated to vertical position, and lowered to its site with a minimum of effort and equipment. These members may also be used for raising the tower. For purposes of illustration, two such buoyant members 48 and 49 have been shown in Figure 1 of the drawings. These buoyant members 48 and 49 are, preferably, identical and, by referring to Figure 4 of the drawings, it will be noted that they are placed and held, respectively, within the vertical pipe col-

umns 32 of the tower section 17 and are secured in fixed position therein by any suitable means.

The buoyant member 48 is preferably positioned considerably below the upper end of the tower, that will support the platform 100, shown in dotted line, and rides partially above the water surface so as to support the tower afloat in its upright position before the tower is sunk to rest upon the water-bed. The buoyant member 49 may be placed in any desired position, but is preferably located adjacent the buoyant base 18. These buoyant members 48 and 49 may be varied in height according to the requirements therefor, but are all of the same horizontal cross section and are provided with a center opening 50, preferably conforming to that of the base 18—i. e., substantially doughnut-shaped—to provide an unobstructed and unrestricted work area or shaft that will permit multiple drilling from a rig or derrick 101 supported on the platform 100, or for other operations, through the entire length of the tower 16.

Each buoyant member 48 and 49 is connected with flooding and venting pipes 51 and 52 terminating at a control point or station 31 having control valves 31a and at which station a sub-platform may be provided for such station and for other auxiliary apparatus, including the "Christmas tree," upon completion of the drilling of the wells. The buoyancy of the members 48 and 49 may be selectively controlled by the means just described—that is to say, water may be admitted through the pipes 51, respectively, to said members 48 and 49 and any air therein may be vented from said members through the pipes 52; and, water thus admitted may be forced out of said members through pipes 51 by admitting air under pressure to said members through pipes 52.

As is to be understood, valves, pumps, and blow out equipment of known standard design and for flooding and emptying any of the buoyant members 18', 48 or 49, are provided at the control station 31 and/or the control station may be connected to similar equipment located at a remote point—say for instance, on a barge or tug which is standing by—all of which is well-known in the art. Inasmuch as the detailed construction of said equipment is no part of the present invention, no illustration thereof has been made beyond a general designation there as shown. A pipe chase 53 extends upwardly from the base 18 through the tower structure for the protection of the pipes 29 and 30, 51 and 52, which extend, respectively, from the buoyant base 18 and the buoyant members 48 and 49.

The uppermost section 54 of the shaft or tower 16 is provided with conventional hoisting windlass means 55 to which are connected chains or cables 56 that may also be connected to anchors, not shown, and which run over idler rollers 57 which are preferably positioned on the tower 16 at, or slightly below, the water lever 67. The lower ends of these cables or chains are to be connected to suitable anchors, not shown, which have been previously set on the water-bed 66 at spaced distances around, and remote from, the site selected for the base 18. While the tower is being located and positioned on the bed of the body of water, the cables or chains are selectively slackened or tightened to adjust and maintain the tower 16 to and in a perpendicular position during the period of positioning and, afterwards, for adding to the stability of the tower and to aid in maintaining the same in a vertical position 75 in times of extreme stress.

In accordance with the present invention, the tower is to be erected on shore and, by reason of its simple design, necessity of costly erection equipment is eliminated. When placing the tower, for example, in water up to fifty feet in depth where the chambered base 18 and one, two or three sections 17 (of about 25 feet each in length or height) comprise the tower 16, the buoyancy of the base alone is sufficient for floating the tower in upright position to the desired location, the base 18 being only partially submerged. Due to its low center of gravity, the tower will not upset or roll over, thus the buoyant members 48 and 49 may be eliminated. With the design and proportions shown, such a tower may be floated upright in approximately 40 inches of water and, in positioning such a tower, of one to three sections, the buoyancy of the sealed columns 32 above the center of gravity take the place of the buoyant member 48 and greatly aid in placement of the tower. During the sinking operation, the more the chambered base 18 is flooded, the more the sealed columns tend to keep the tower in an upright position. Of course, if desired, a buoyant member 48 of appropriate dimensions may be used with a tower comprising a base and three or more sections, either for floating the tower in upright position to location or in a horizontal position and for controlling its placement in position.

For towers made up of more than three sections and the base, there is shown in Figures 11 to 15 inclusive of the drawings, one method of transportation. This method is used where certain considerations or problems prevent towing afloat the entire buoyant structure to the point of location of its placement. In such case, it will be seen that there is employed a scow 58 for transporting a relatively high or long tower, the interior of which barge or scow is hollow and divided longitudinally, as at 58a, to provide a pair of control compartments 59 and 60, from which extend pipes 61 and 62, respectively. The deck of the barge is provided with transversely extending skidways 63, and skids 64 are attached to the tower by means of the cables 65.

With the tower in position on, and secured to, the barge 58, said barge is then towed to the desired site or location in the water. In order to release the tower from the barge, the tower is unsecured therefrom and the compartment 59 thereof is flooded through the pipe 61, causing the barge to assume the position shown in Figure 13 of the drawings. At this time, through the medium of the skids 63 and 64, the tower will be launched sidewise in a horizontal position. The buoyancy of the control members 48 and 49 and the base 18 will allow the tower to ride in a horizontal position, though partly submerged.

After launching from the barge, the tower may be floated to the area where it is to be positioned. Then, by flooding the lower buoyant members 49 and/or 18, the tower will assume an upright position, as shown in Figure 14. The upper control buoyant member 48 is designed so that when it is empty it will carry or support the entire dead load of the structure and will buoy the tower so that it will remain slightly above the bed 66 of the body of water 67. In this position, the tower may be manipulated into place over the desired spot on the bed 66 upon which it is to rest. Subsequent controlled flooding of the upper buoyant member 48 (and of the buoyant member 49 if not completely flooded, or of the buoyant base mem-

ber 18) causes the tower to settle slowly onto the bed 66.

In water having a certain degree of motion, the movement imparted to the tower will cause the cutting bars 27 to scour a seat for the base 18 as the tower settles. When resistance of the structure in contact with the water-bed prevents further movement, the tower is maintained in a vertical position by adjustment of the control cables 56 and by the controlled flooding of the buoyant members 18, 48 and 49, which may be flooded to the extent required to provide sufficient weight to prevent the base of the tower from creeping. When there is no motion of the water, or the consistency or character of the bed 66 is such that the scouring process is insufficient to provide a suitable seat, other practical means, such as a hydraulic jet, may be employed to obtain a proper bearing.

While the invention may be practiced without the columns 32 of the framework being hollow and sealed, the employment of this feature in combination with the other features of this invention has many advantages—among which are, (1) providing a strong structure with a minimum of surface subjected to corrosive elements and (2) the hollow sealed columns contribute to the buoyancy of the structure, by reducing its specific gravity, and, when sinking the tower to the water-bed while in vertical position, furnish that necessary buoyancy desirable to control the positioning of the tower, thus permitting the control buoyant member 48 to be of smaller size and dimensions resulting in less cost.

Consequently, referring to Figure 14, with the columns 32 hollow and sealed, the buoyant member 48 is computed and designed, with respect to the weight of the entire tower, to have an excess displacement over the amount necessary for net buoyancy—i. e., to sustain afloat the entire dead load of the tower as shown in Figure 14 with the base chamber 18' and/or the buoyant member 49, or vice versa, completely flooded as may have been estimated for a given tower to be erected and positioned in place. To this end, the dimension or area A (Fig. 14) represents the gross displacement; dimension B represents displacement to sustain said dead load; and dimension C represents the excess displacement for control of the tower and to allow for variations in estimated weight, but less the buoyancy afforded by the sealed columns 32.

Therefore, in computing the displacement of the buoyant member 48, the area or dimension E of the tower (above the waterline) is computed at its full weight while the portion or area D (below the waterline in Fig. 14) is figured at approximately $\frac{1}{8}$ of its full weight, due to the specific gravity being about 1 to 8, whereby the structural members of the submerged portion of the tower lose $\frac{1}{8}$ of their weight by displacement which is a gain of about 100 pounds in buoyancy, per linear foot submerged (with the tower as at present designed), and to which is to be added the net air spaces within the sealed columns 32, amounting (in the tower as at present designed) to about 9.6 cubic feet or approximately 600 pounds per linear foot of the submerged portion of the tower, thus making a total of about 700 pounds per linear foot submerged.

Now, with the tower as shown in Fig. 14 having either or both of the buoyant chambers 18' and 49 flooded and with buoyant member 48 empty, the bottom of the base 18 may be estimated to be about 15 feet (distance F) above the

water-bed 66, or in any event, above the point on which it is to finally rest, and the tower will be sustained afloat in that position with the dimension C of member 48 above the water surface. When it is desired to sink the tower further, the dimension B of the buoyant member 48 will be flooded—to an amount equal to the dimension C—as indicated by the line C'. In other words, the volume of air equal to the dimension B is displaced upwardly within the member 48 by the admission of water into the dimension B in an amount substantially equal to the dimension C.

In this condition, the member 48 will become awash because the load then equals the buoyancy. It can be readily understood that after the dimension C of the member 48 (or, in other words, the entire buoyant member 48) goes below the surface of the water, there should be some buoyancy above that point to keep the tower from sinking and this is provided by the captive air in sealed columns 32 in the dimension E above the waterline. In view of the above computations, which have been used by way of example, the tower now may be sunk further for a distance of one foot for every 700 pounds of water admitted to the buoyant member 48 (over and above the amount C' that has been already admitted). Consequently, when F' (the dimension of the tower above the waterline and corresponding to the distance F between the base 18 and the water-bed 66) multiplied by 700 pounds of water has been admitted to the member 48, in addition to the amount C', the tower base will be on or adjacent the water-bed 66 but will be still suspended afloat by enough buoyancy to keep any pressure off the base 18 of the tower.

The operation of the proper valves at station 31, or at other remote places, will stop this sinking movement at any time and at any stage, and, conversely, will initiate sinking or, by blowing out the member 48, raise the tower to selected levels. While so suspended, the motion of the tower due to surface motion of the water, will agitate the tower so that water will be squeezed or compressed in and out of the space between the base 18 and the water-bed 66, causing loose material to be obliterated and, in the case of heavy material, the cutting bars 27 will break said material loose to be washed out. Eventually, there will be nothing but bare soil or a bearing surface conforming to the under-surface of the base 18. As previously stated, when there is no such surface motion of the water which will agitate the tower, hydraulic jets may be employed where necessary.

It will be appreciated that a very small amount of water admitted to or blown out of buoyant member 48, under the conditions above mentioned, will give an appreciable amount of control. When a seat or bearing surface for the base has been thus made and the base seats itself properly, the control valve at the station 31 will be open wide to flood the buoyant member 48 completely which, of course, puts the full load of the tower on the water-bed 66. During the time of setting the tower, the upright position of the latter is controlled by means of the winches 55 operating on the anchored cables 56. As above indicated, if an additional weight is needed for maintaining the tower on its seat on the water-bed, the water in the chamber 18' of the base may be blown out and cement substituted therefor.

A platform 100 as well as derricks, drilling or mining rigs 101 may be mounted on the upper-

most section 17 to conform to any use to which the tower may be put. In the illustrated embodiment of the invention, a wide clear working space has been provided down through the center of the shaft or tower for drilling any convenient number of wells, or for other purposes.

If for any reason it is desired to remove the tower to another location or to recover the same, complete salvage may be effected by reversing the method employed in positioning the tower on the bed of the body of water.

For the purposes of the following claims the terms "buoyant member" or "buoyant members" may refer to either the base chamber 18' or the members 48 or 49; and the term "at or adjacent the base," which defines the disposition of certain of the buoyant members, shall refer to and mean either or both of the parts 18' and/or 49.

To summarize some of the advantages of the tower, according to the present invention, the tower—

1. May be transported in a horizontal position, either in the water, where it floats partially submerged, or on a barge or scow from which it is discharged in a horizontal position to float;
2. May be used in any water location or marshy location;
3. May be transported and positioned without the requirement of specially constructed equipment, thus eliminates costly erection equipment;
4. Requires a minimum of offshore operation in placing and putting into use;
5. Provides its own base and means of securing same on bottom of body of water or in marshy locations;
6. Provides means for scouring its seat securing a firm seating or bearing for seating itself on bottom of bed or other location;
7. Has full salvage possibilities;
8. May be constructed and erected to any desired height (within design limits, which will vary) by adding like sections of interchangeable parts and sections;
9. Has its framework and base arranged so as to provide open and unobstructed space within framework and base full length of tower and base;
10. Reduces resistance of external forces to a minimum;
11. Has its base formed by a reinforced structure designed and constructed to support and distribute the weight of the load of the tower, platform and the load placed on platform;
12. Has its base enclosed to form a watertight floodable chambered buoyant member that may increase the weight and stability of the tower by flooding said member with concrete after the tower is in position;
13. Has buoyant members fixed within certain sections, equipped with means for flooding and blowing out for controlled buoyancy, and spaced in such manner as to facilitate controlling, floating, sinking, raising, scouring, placing and anchoring tower, and may be used for storage or other purposes while tower is in use;
14. Has sections 17, and parts thereof, interchangeable with each other;
15. Has sections 17 individually braced horizontally, transversally, cross-braced, and vertically, so as to provide an unobstructed interior work shaft throughout length of tower;
16. Has controllable control-buoyant-members fixed and within framework of tower that do not obstruct the open work shaft or space within the tower;

17. May have other control-buoyant-members added as desired or necessary;

18. Has hollow, sealed, air-containing supporting columns, or like members, in its framework that reduce the specific gravity of the tower and increases the control of the tower in sinking or raising same and that furnish added buoyancy at regular intervals about and throughout the length of the tower;

19. May be anchored by means of guy chains and anchor means which provides and allows greater control and safety;

20. Provides means of overcoming, or avoiding, creeping or shifting of the base;

21. May be seated, or set, by hydraulic jet when necessary;

22. Is more economical to construct and place than other devices for similar purposes; and

23. Is a single unit, composed of interchangeable sections, and parts thereof, a base and other buoyant members.

Obviously many modifications and operations of the invention as hereinabove set forth may be made without departing from the spirit and scope thereof, and therefore only such limitation should be imposed as are indicated in the appended claims.

What I claim as new is:

1. A floatable structural marine tower, to rest on a water-bed and extend above the surface of the water to support a superimposed load thereupon, comprising a hollow annular-like watertight casing forming a buoyant base to rest upon the water-bed, an open framework to support said superimposed load and extending from said base and arranged about the central opening in said base, and means for controllably flooding and emptying said base; said framework and the opening in said base defining an unobstructed open-work-area or shaft extending the length of the tower to allow multiple drilling operations through the center of the tower.

2. A floatable structural marine tower adapted to rest upon a water-bed and comprising a framework to support superimposed loads and including an annular-like base to support said framework upon the water-bed, a fixed controllable buoyant member within said framework and disposed at a point remote from the base to aid in positioning said tower; said base, buoyant member and framework being arranged to define a central work space or shaft extending therethrough longitudinally of the tower.

3. A floatable marine tower adapted to rest upon a water-bed to support a superimposed load thereupon comprising a hollow annular-like base, a framework secured to and extending from said base and disposed about the central opening in said base, annular-like buoyant means carried by said framework and spaced from said base, the opening in said base and buoyant means being in substantial alignment, controllable means connected with said base and buoyant means for selectively flooding and emptying said base and buoyant means when floating or positioning said tower.

4. A floatable marine tower adapted to rest upon a water-bed to support a superimposed load thereupon comprising a hollow annular-like base, a framework secured to and extending from said base and including a plurality of hollow sealed columns, containing captive air, disposed about the central opening in said base and extending the length of the tower to at least its estimated waterline, annular-like buoyant means carried by

said framework and spaced from said base, the opening in said base and buoyant means being in substantial alignment, controllable means connected with said base and buoyant means for selectively flooding and emptying said base and buoyant means when floating or positioning said tower.

5. In a structural marine tower comprising an annular-like base defining a central work opening therethrough, a framework extending vertically from said base when the tower is in upright position, said framework being arranged relative to the opening in said base to define a central work area longitudinally of the tower, said base including a watertight casing embodying means for distributing the vertical load imposed thereon concentrically throughout the base, the interior of said casing being hollow for buoyancy, and other buoyant means disposed on the tower at a point or points along said framework.

6. In a floatable structural marine tower to rest on a water-bed and extend above the surface of the water to support a superimposed load thereupon, a hollow annular-like watertight casing forming a buoyant base to support the tower upon the water-bed, a framework to support said superimposed load and extending from said base and including bearing columns that are hollow and sealed and containing captive air, to decrease the specific gravity of the structure and increase the control of the structure when in water, and that extend the length of the tower at least to its estimated water line and that are arranged at intervals and secured to said base,

25 30 35 40 45 50 55 60 65 70 75

bracing for said columns; and means for controllably flooding and emptying said buoyant base.

7. A structural marine tower comprising an annular-like base defining a central work opening therethrough, a framework extending vertically from said base when the tower is in upright position, said framework being formed of a plurality of superimposed interchangeable sections, each of said sections including hollow sealed columns arranged to extend in the general direction of the length of the tower and at intervals about said opening in said base, means uniting said columns to define a central work space or area longitudinally of said tower, a controllable buoyant means carried by said tower, and means for controllably flooding and emptying said buoyant means.

8. A structural marine tower as set forth in claim 7 further characterized by the base being polygonal or circular-like and said columns being arranged substantially concentrically of said base, about the opening in said base, and said base including a stiffened watertight hollow casing forming a controllable buoyant means.

9. A structural marine tower including a base, a framework extending vertically from said base, said framework formed of a multiplicity of superimposed interchangeable sections, said base comprising a stiffened watertight casing the interior of which is hollow for buoyancy, and cutting bars secured to the bottom face of said base to aid in positioning said tower on the bed of a body of water.

10. A structural marine tower including a circular-like base, a framework extending vertically from said base, said framework formed of a multiplicity of superimposed interchangeable sections, said base comprising a stiffened watertight casing the interior of which is hollow for buoyancy, controlled means within said tower to per-

mit location and settling thereof in a body of water, and cutting bars secured to the bottom face of said base to aid in positioning said tower on the bed of a body of water.

11. A structural marine tower comprising a base, a tower framework extending vertically from the base when the tower is in upright position, control buoyant members, at least one of said members being at or adjacent the base and at least another disposed adjacent the normal or estimated lower-water line of the tower when erected into position, and means connecting said buoyant members to instrumentalities for controllably flooding the same or for removing the water therefrom, whereby the tower may be floated into position and be permitted to settle and to rest in a vertical position with its base on the bed of a body of water.

12. A structural marine tower comprising a hollow watertight base, a tower framework extending vertically from the base when the tower is in upright position, said framework comprising a multiplicity of columns disposed substantially concentrically about the center of the base, one or more chambered buoyant members disposed at intervals along the length of the tower to provide buoyant means for floating the tower to location, and means connecting said buoyant member or members and said base to instrumentalities for controllably flooding the same or for removing the water therefrom whereby the tower may be floated into position and be permitted to settle and to rest in a vertical position with its base on the bed of a body of water.

13. A structural marine tower comprising a base, a framework extending from the base and formed of a plurality of superimposed interchangeable sections, each of said sections including columns arranged substantially concentrically about the base, and bracing means for said columns, one or more control chambered buoyant members disposed between said columns and said bracing means of certain of said sections, and means connecting said buoyant member or members to instrumentalities for controllably flooding the same or removing the water therefrom, whereby the tower may be floated horizontally into position, manipulated to a vertical position and be permitted to settle and to rest in a vertical position with its base on the bed of a body of water.

14. A structural marine tower, adapted to rest upon the bed of a body of water and extend above the surface of said body of water, comprising a unitary framework including a plurality of supporting columns, said columns being hollow to provide buoyancy to the structure, buoyant chambered members disposed along the length of the tower, at least one on each side of the center of gravity of the tower, whereby the tower may be floated horizontally to location where it is to be positioned, means connecting said buoyant members to instrumentalities for controllably flooding the same and for removing water therefrom, whereby upon flooding of one of said buoyant members, the tower will become upright in the water and suspended afloat over said location and, then, by admitting water to the other of said buoyant members, the tower may be sunk and manipulated to settle and rest upon the water-bed in a vertical position.

15. A structural marine tower as set forth in claim 14 wherein, when the tower is in said upright suspended position, the buoyant capacity of the upper buoyant member, in combination

with the buoyancy of said submerged hollow columns, being sufficient to sustain the structure afloat in an upright position with a portion of the columns extending above the water's surface, the buoyancy of said columns being insufficient to float said structure when said buoyant member is rendered non-buoyant, the buoyancy of said upper member being controlled by said instrumentalities and when rendered non-buoyant to a degree that balances with the load, the buoyancy of the columns above said upper buoyant member affords such buoyancy sufficient to support the tower afloat, whereby further admission of water to said upper buoyant member results in nicety of control of the afloat position of tower for setting the tower and scouring a seat for it before resting on said seat on the water-bed.

16. In a floatable structural marine tower to rest on a water-bed and extend above the surface of the water to support a superimposed load thereupon, a hollow annular-like watertight casting forming a buoyant base to support said tower upon the water-bed and having a central work opening therethrough, a framework to support said superimposed load and extending from said base and including hollow sealed bearing columns containing air and arranged at intervals about said opening in and secured to said base and bracing for said columns, and means for controllably flooding and emptying said base, the framework and the opening in said base defining an unobstructed work area or shaft extending the length of the tower to allow multiple drilling operations through the center of the tower.

17. The method of positioning a marine tower in place on a water-bed, which tower comprises a framework with at least two controllable chambered buoyant members, one on each side of the center of gravity of the tower, said method including floating the tower in a horizontal position to the point of location where the tower is to be erected, then flooding one of said buoyant members to bring the tower to an upright position and supporting the same in that position by the other of said buoyant members, then controllably flooding the said last-mentioned buoyant member to allow the tower to settle downwardly to rest upon the water-bed.

18. The method of positioning a marine tower in place on a water-bed, which tower comprises a framework with a base end and a controllable chambered buoyant member carried by the tower and positioned on the side of the center of gravity of the tower opposite that of the base end of the tower, said method including supporting the tower afloat in a body of water in an upright position by said buoyant member with the base end of the tower above the water-bed, and controllably flooding said buoyant member to sink the tower so that its base end will contact but not be supported by the water-bed, whereby surface motion of the body of water will cause the base end of the tower to form a bearing seat on the water-bed, and then further flooding said buoyant member to bring the base end of the tower to rest on the water-bed.

19. The method of positioning marine towers in place, which towers may be built-up on land or on a floating barge and comprises spaced buoyant members, one of which is positioned at or adjacent to the base of the tower, said method comprising floating the tower in a horizontal position, then flooding a buoyant member at or adjacent the base of the tower to bring said tower to a vertical partly submerged position, and manipulating

the tower, as the flooding of said buoyant member is continued, or the flooding of another buoyant member is commenced, to settle the tower downwardly and to bring the base to rest on the bed of the body of water.

20. The method of positioning marine towers in place, which towers may be built-up on land or on a floating barge and which include spaced buoyant members, one of which is positioned at or adjacent to the base of the tower, said method comprising disposing the tower upon the barge horizontally, then transporting the barge to the general area where the tower is to be located, then discharging the tower from the barge while the tower is in a horizontal position thereon whereby the tower becomes afloat in a maneuverable horizontal position, then flooding the buoyant member at or adjacent the base of the tower to bring said tower to a vertical partly submerged position, and settling the tower downwardly by further flooding said buoyant members or one of said buoyant members to bring the base of the tower to rest on the bed of a body of water.

21. The method of positioning marine towers in place, which towers may be built-up on land or on a floating barge and which comprises spaced buoyant members, one of which is positioned at or adjacent the base of the tower, and which said barge is provided with at least one control buoyant member, said method comprising disposing the tower upon the barge horizontally, then transporting the barge to the general area where the tower is to be located, then flooding said control buoyant member of said barge to tilt said barge for discharging the tower therefrom whereby the

5 tower becomes afloat in a maneuverable horizontal position, then flooding a buoyant member at or adjacent the base of the tower to bring said tower to a vertical partly submerged position, and—as the flooding of said buoyant member of said tower, or another of said buoyant members of said tower, continues to further settle the tower—bringing the base of the tower to rest on the bed of the body of water.

10 22. The method of positioning marine towers in place as set forth in claim 19, further comprising selectively slackening and/or tightening 15 remotely anchored guy means connected with the tower to adjust and maintain the tower to and in substantially perpendicular position, during the period the tower has assumed a vertical position by flooding certain of said buoyant members and is settling to water-bed; and, thereafter, for adding to the stability of the tower and aid in 20 maintaining the same in a vertical position in times of extreme stress.
